FIRE TUBE FURNACE WITH FLUE GAS TURBULATOR

Walter B. Brock, Vernon, N. Y.

Application July 1, 1949, Serial No. 102,697

3 Claims. (Cl. 110—97)

1

My invention relates to a flue gas turbulator, and I declare the following to be a full, clear, concise and exact description thereof sufficient to enable anyone skilled in the art to which it appertains to make and use the same, reference being had to the accompanying drawings in which like characters refer to like parts throughout.

The object of the invention is to provide a device that can be removably mounted in the internal flues or fire tubes of a boiler or other fuel burning device to conserve the heat generated by the fire and thereby prevent its escape up the chimney.

Heretofore in a heating system or fuel burning device, a substantial percentage of the fuel burned is wasted for the reason that the hot core of the combustion gases passes directly through the flues and out the smoke pipe carrying with it a large percentage of the heat up the chimney.

The flue gas turbulators herein provided are placed in one or more of the internal flues or fire tubes of the heating system or fuel burning device to retain the heat which would otherwise escape, and thereby transfer said heat into hot water, or steam, or warm air.

The turbulator achieves its object by having a plurality of heat absorption and gas deflection surfaces which retard and break up the forward coming stream of combustion gases, and direct them outwardly and downwardly toward the heat absorption surfaces of the flues or fire tubes where said gases can then more readily transfer their heat units to the medium to be heated. At the same time the turbulator itself absorbs heat from the combustion gases and reradiates it to the flues or fire tubes.

Functionally speaking, the turbulator floats centrally in the stream of combustion gases, creating no obstruction to the heat absorption area of the flue, and preventing any tendency of the outgoing flue gases to form a hot core which would carry the heat out the chimney without coming in contact with the flue walls. The result of this action is a much higher percentage of heat transfer through the flue walls and a substantial drop in the stack temperature.

This will be better understood by referring to the drawings in which:

Fig. 1 is a perspective view of a standard type of boiler showing a turbulator installed in one of the flues of said boiler, parts being broken away.

Fig. 2 is a detail enlarged view showing the turbulator in perspective.

2

Fig. 3 is a detail enlarged view showing a plan of the turbulator.

Fig. 4 is a detail view showing a modified form of the turbulator disposed in a round fire tube such as used in marine type boiler, parts being broken away to expose the modified form of turbulator.

Referring more particularly to the drawings, a boiler 1 of the usual construction having fire tubes 2 as illustrated in Fig. 1. The novel feature comprises the addition of removable turbulators 3 to said fire tubes 2.

Each of the turbulators 3 comprises a single strip of metal 4 bent to form a series of substantially parallelogrammatic plates 5 disposed at right angles to each other with every other plate 5 lying in a plane parallel to one another.

Furthermore, each of the plates 5 of strips 4 is tilted towards one end by bending said strips 4 on parallel lines 6 inclined at an angle of approximately sixty degrees to the lower edge 7 thereof, whereby said plates 5 will cause the deflection of the hotter gases in the upper portion of the stream passing through tubes 2 downward toward the comparatively cooler layer of gas which tends to cling to the lower surface 8 of the flue.

Moreover, each of the strips 4 is supported on legs 10 which are welded or otherwise attached to the lower part of strips 4 at suitable distances apart to hold said strips 4 up off the lower inner surface 8 of fire tube 2, whereby to form a passage therebeneath for the hot gases of combustion.

Furthermore, the top edge of each of the strips 4 is spaced a suitable distance from the inner top surface 12 of fire tube 2 for the same purpose.

Referring more particularly to Figs. 2 and 3 and commencing at the left hand end thereof the turbulator comprises an end plate 15 that is substantially rectangular throughout part of its surface. It is cut downward at 16 a short distance at an angle from its top edge 17 to the right angle bend 6 between end plate 15 and adjoining plate 19 to form a V-shaped member 20 that is bent at substantially right angles to plate 19, whereby to provide a supporting arm to aid in holding turbulator 3 at a suitable distance from the side wall 21 of fire tube 2 and to provide a surface for the additional retarding and turbulating action on the progressing stream of combustion gases.

Plate 19 is rectangular throughout part of its surface and is disposed substantially at right angles to end plate 15. Likewise plate 19 is cut down at 16 to form a V-shaped member 25 similar

to member 28 bent at right angles to plate 19 and extending in the opposite direction to V-shaped plate 20 to aid in holding turbulator 3 from the opposite side wall 21. It is used for the same supporting and retarding purpose as V-shaped member 20.

Adjoining plate 19 on the right is plate 26 similar in shape to plate 19. It is disposed at right angles to plate 19 and in a plane parallel to the plane of end plate 15. It is cut down also at 16 to allow for a V-shaped member 20 on plate 32 next to the right.

Progressing further to the right, plate 33 is similar in shape to plates 19, 26 and 32. It is provided with a V-shaped member 25 extending therefrom in the opposite direction to member 20 of the plate 19 and 32 and parallel to member 25 of plate 19.

Plates 35 and 36 are similar to plates 19, 26, 32, 33 and are provided with V-shaped members 20 and 25 respectively. It will be observed that V-shaped members 20 alternate with V-shaped members 25, whereby all V-shaped members 20 extend in parallel relation to each other to one side of the turbulator 3 and V-shaped members 25 extend in parallel relation to each other to the other side of turbulator 3, whereby to aid in keeping turbulator 3 in its proper position in flue 2.

The end plate 40 is of mutilated rectangular shape. It is provided likewise with a V-shaped member 20.

A modification of the turbulator 3 here denoted 45 is illustrated in Fig. 4. It is made preferably of one piece of metal bent to form parallelogrammatic shaped plates 51 at substantially right angles to each other with each alternate plate lying in a parallel plane. Plates 51 are tilted as in the former construction by bending along lines 52 that are disposed at an angle of approximately sixty degrees to lower edge 53 thereof, whereby to direct the gases downward.

It is used in a round flue or fire tube 55. The legs 10 of the former structure are omitted for the reason that they are unnecessary to keep it properly spaced from the contiguous wall of tube 55 or to prevent it from obstructing the passage of gases as they progress through said tube 55.

The combustion gases easily pass all around said turbulator 45 which serves to retard their flow and to break up the central core of hot gases that ordinarily forms in such flues, and to deflect said gases against the heat absorption surfaces of the flue 55.

Operation

Turbulator 3 will be disposed in the fire tubes or flues 2 of boiler 1. To this end door 60 of boiler 1 can be opened. Assuming that the gases of combustion are progressing from the right hand side of each of the fire tubes 2 as illustrated by the arrows in Fig. 1 they will meet first the surface of end plate 40 which is disposed at an angle to the direct flow of said gases. This end plate 40 will aid in retarding the passage of said gases and direct them downward and towards the surface of side wall 21.

Moreover, V-shaped member 20 connected to end plate 40 will also aid in retarding the upper strata of gases and in directing them sidewise and downward toward the lower surface 8. As said gases progress further they will be retarded and directed alternately towards the side 21 and the lower surface 8 of fire tube 2.

Turbulator 3 being centrally disposed in the path of the progress of the combustion gases will prevent any tendency of the outgoing flue gases to form a hot core at the center of the fire tube and thereby carry the heat directly to the chimney without coming in contact with the walls of fire tube 2. In doing this it creates no obstruction to the heat absorption area of the fire tube 2 for the reason that the open spaces provided at the top, bottom and sides of the turbulator 3 allow for the passage of said gases.

Moreover, the turbulator 3 scatters said hot core of gases and deflects them outwardly and downwardly towards the heat transfer surfaces 8 and 21 of fire tube 2, thereby scrubbing loose the layers of cooler gases which cling to said surfaces.

The resultant effect of this turbulence of the gases is a higher percentage of heat transfer through the said walls 8 and side 21 of fire tube 2 and a substantial drop in the temperature of the gases leaving fire tube 2.

Having thus described my invention what I claim as new and desire to secure by Letters Patent is as follows:

1. In a flue gas heater having substantially horizontal fire tubes or flues, the combination with a turbulator positioned within any of said tubes or flues, said turbulator consisting of a strip of metal bent to form a series of alternating right and left hand deflecting plates, the alternate pairs of right and left hand deflecting plates lying in parallel planes to each other, the axis of the bends between the respective plates disposed at an oblique angle to the edges of the turbulator strip.

2. In a flue gas heater having substantially horizontal fire tubes or flues, the combination with a turbulator positioned within any of said tubes or flues, said turbulator consisting of a strip of metal bent to form a series of alternating right and left hand deflecting plates, the alternate pairs of right and left hand deflecting plates lying in parallel planes to each other, the axis of the bends between the respective plates disposed at an oblique angle to the edges of the turbulator strip, so as to form a series of deflectors, the face of each deflector plate being inclined at an oblique angle to the horizontal axis of said tube or flue.

3. The structure recited in claim 1, said turbulators being removably mounted in said flues, and means for supporting said turbulators within said flues with the faces and edges of the deflecting turbulator plates disposed in spaced relationship from the inner wall surfaces of said flues.
